UNITED STATES PATENT OFFICE.

PAUL A. MEEHAN, OF CLEVELAND, OHIO, ASSIGNOR TO AMERICAN DRESSLER TUNNEL KILNS, INC., OF CLEVELAND, OHIO, A CORPORATION OF NEW YORK.

TUNNEL KILN.

Application filed July 7, 1926. Serial No. 120,903.

The general object of my present invention is to provide an improved circulation system for tunnel kilns. More specifically, the object of the present invention is to provide simple and effective means for maintaining a forced circulation of the atmosphere of a kiln by the impelling action of jets of heated air or gas forced into the kiln chamber. The invention is especially applicable to tunnel kilns of either the muffle or direct fire type, but may also be used with periodic down-draft and other types of intermittent kilns.

These and other features of novelty which characterize my invention are pointed out with particularity in the claims annexed to and forming a part of this specification. For a better understanding of the invention, however, its advantages and specific objects attained with its use, reference should be had to the accompanying drawings and descriptive matter in which I have illustrated and described preferred embodiments of this invention.

25 In the drawings:

Fig. 1 is a side view of a portion of a tunnel kiln including the entrance section and preheating zone;

Fig. 2 is a section of the muffle kiln on the line 2—2 of Fig. 1;

Fig. 3 is a section showing my invention applied to a kiln of the direct fired type;

Fig. 4 is a section of a direct fired kiln showing a modified form of my invention;

35 and

Fig. 5 is a modified form of the last injector.

In the drawings, a tunnel kiln A is shown having a kiln chamber through which move the cars B carrying ware C which is to be heat treated. Longitudinally spaced along the top of the preheating zone of the tunnel kiln are openings to the kiln chamber crown and in these openings are arranged the injecting means. My invention is of especial value in connection with the preheating zone of the kiln. However, the principle and application can be used wherever a forced circulation is desirable.

50 In the muffle kiln chamber, as shown in Fig. 2, with the combustion chambers D located along the side walls and the ware car on tracks along the middle portion of the kiln, the natural convection circulation of the kiln atmosphere is upwardly from

the combustion chambers D to the kiln crown, downwardly through the ware stacks along the center line of the kiln and through the refractory body passages to the sides of the kiln chamber. The impelling jets of the present invention are designed to increase the atmospheric circulation along the paths of the natural convection circulation.

Arranged in each of the openings in the top of the kiln chamber is an impelling jet apparatus consisting of a hollow casting G' supported on the kiln crown by the flanges G² and serving as a support for a series of injecting and mixing nozzles K², K³, and K⁴ through which passes the impelling jet from a nozzle K'. The injecting nozzles K², K³, and K⁴, supported by brackets G⁴ and G⁶ on an inner flange G⁶ of the hollow casting, consists of three downwardly tapering elements with circular inlets and outlets of increasing diameters, and the outlet of each of the upper nozzles extending slightly into the inlet of the next lower nozzle. On top of the casting G' is positioned a removable cover plate G³ and through the center of which projects a pipe F³ having the nozzle K' secured to the end thereof. The lowermost nozzle K⁴ is shown with a circular discharge portion. A modified form of this discharge outlet is shown in Fig. 5 as being fan shaped with a rectangular base, the greater dimension of the base extending parallel to the longitudinal center line of the kiln.

The car B is arranged with the ware C stacked on both sides of the car leaving a vertical passageway C' down through the middle of the ware. In the refractory bodies forming part of the ware supporting means of the car are located circulation passages C² opening to the passage C' and to the sides of the kiln chamber at the bench level of the kiln. In the side walls of the kiln chamber are positioned pipes H opening to the atmosphere and to the kiln chamber. The pipes H are shown with removable plugs in the outer openings, the plugs being removed when an outlet to the atmosphere is necessary. Connecting pipes H' for the spaced pipe openings H are shown in Fig. 1. Arranged in the kiln chamber walls are the pipes H² and H³ connecting the pipes H to the mixing chamber at the kiln crown. Passages H⁴, H⁶, and H⁸ are formed about the bottom and sides, respectively, of the com-

bustion chambers D and open to the kiln chamber at the bench level and below the kiln crown.

Along the top of the kiln is a supply pipe E for the hot gases from the recuperator or some other suitable source. The pipe E is connected to branch pipes F' each of which is provided with a control valve F² and is connected to one of the pipes F³. The valves F² are used to control the supply of hot gases to the pipes F³ and are especially useful when an injector is to be inspected or removed for repairs.

The circulation of the kiln atmosphere follows the paths shown by the arrows. The hot gases from the main E under pressure are ejected from the nozzle K' into the mixing chamber G' where stages K² and K³ draw on the atmosphere at the kiln crown. The resulting mixture of hot gases and kiln atmosphere flows under pressure through the last stage of the injector K⁴ which exerts an impelling action on the atmosphere at the top of the kiln chamber. The stream of mixed gases which flows downwardly in the passage C' between the ware stacks, is divided into separate streams by the passages C². Part of each stream flows to the kiln crown through the pipes H, H² and H³ where it enters the mixing chamber G'. The remaining portion flows upwards through the passages H⁴ and H⁵ to the top of the kiln chamber where it mixes with the impelling jet in the nozzle K⁴. It is apparent that the forced circulation of the kiln atmosphere follows the natural convection circulation paths of flow which is very desirable. The longitudinal flow of the kiln atmosphere is restricted by baffles A' in the usual manner.

The impelling jets can be introduced into the kiln chamber at various points depending upon the type of kiln in which it is to be installed and the desired circulation of the kiln chamber atmosphere. In Figs. 3 and 4 are shown two modified forms of the injection system applied to direct fired kilns. The circulation of the kiln atmosphere is shown by the arrows. In a direct fired kiln the injection gases may be taken from the kiln itself or from the exhaust fan.

The former constructions where a forced circulation of the kiln atmosphere was desirable, a multiplicity of fans at various points along the kiln were necessary. Great difficulty and expense were incurred by the deteriorating action of the hot gases on the propelling mechanism. In the present invention, a single fan (not shown) is sufficient to force the hot gases from the recuperator or some other suitable source such as kiln cooling zone under sufficient pressure to distribute the gases to the spaced nozzles.

In cases where outside air is introduced

into the kiln in this way, the excess added to the kiln atmosphere will be exhausted by a fan located in the entrance end of the kiln to control the longitudinal flow of the kiln atmosphere.

While in accordance with the provisions of the statutes, I have illustrated and described the best forms of my invention now known to me, it will be apparent to those skilled in the art that changes may be made in the forms of the apparatus disclosed without departing from the spirit of my invention, as set forth in the appended claims and that certain features of my invention may sometimes be used to advantage without a corresponding use of other features.

Having now described my invention, what I claim as new and desire to secure by Letters Patent is:

1. In a kiln, means for circulating the kiln chamber atmosphere comprising a channel in the kiln chamber wall opening to the kiln chamber at separated points and an injector having a mixing chamber adjacent one of said channel openings.

2. In a kiln, means for circulating the kiln atmosphere comprising a channel in the kiln chamber wall opening to the kiln chamber at the bench level and top of the kiln and an injector having a mixing nozzle in one of said openings.

3. In a kiln, means for circulating the kiln atmosphere comprising a channel in the kiln chamber wall opening to the kiln chamber at separated points and an injector consisting of a series of mixing nozzles located in one of said channel openings.

4. In a kiln, means for circulating the kiln atmosphere comprising a channel in the side wall of the kiln chamber opening to the chamber at separated points and an injector comprising an injection nozzle and a series of superposed mixing nozzles located in one of said openings.

5. In a circulation system for a tunnel kiln, the combination with a ware supporting kiln car, of a superposed series of injecting nozzles located in the kiln crown, circulation passages through the side walls of the kiln and the body of said car, and means for passing hot gases under pressure through said nozzles to establish a force circulation system through said ware car and the side walls of the kiln.

6. A circulation system for a tunnel kiln comprising a series of superposed injecting nozzles, and means for passing heated gases through said injecting nozzles to establish a forced circulation system in said kiln.

7. An injection circulation system for a continuous tunnel kiln, comprising injection nozzles spaced longitudinally in the pre-heating zone, means for passing heated gases under pressure to said nozzles and means cooperating with said nozzles for utilizing

the nozzle jets to establish a forced circulation of the kiln atmosphere.

8. In a tunnel kiln, an injector for accelerating the kiln atmosphere circulation comprising a superposed series of downwardly tapering nozzles supported in an opening in the kiln crown, the inlet and discharge openings of said nozzles being of increasing area.
9. In a continuous tunnel kiln, a circulation injector system comprising a series of superposed nozzles forming a multi-stage injector, several stages of which draw on the kiln atmosphere and a stage drawing on the external atmosphere.
10. In a continuous tunnel kiln, a series of injecting nozzles located in the preheating zone portion of the kiln chamber, means for passing heated gases into the kiln chamber through each of said nozzles, and circulation passages formed in the walls of said
- 5 kiln chamber and each opening to the latter at spaced points, one of which is adjacent a corresponding injecting nozzle, whereby the jets discharged by said nozzles set up 25 a circulation of the kiln atmosphere.
11. In a tunnel kiln, the combination with an injector nozzle in the kiln chamber, of a kiln car carrying ware to be heat treated through the kiln chamber, said car being 30 formed with circulation passages adapted to communicate with passages which the ware on the car may be stacked to provide, means for passing a gaseous medium through said nozzle to thereby accelerate the circulation 35 of the kiln atmosphere through said circulating passages.

Signed at Cleveland, in the county of Cuyahoga and State of Ohio, this 30th day of June, A. D. 1926.

PAUL A. MEEHAN.
